UNITED STATES PATENT OFFICE.

WILLIAM ELLSWORTH, OF ASHLAND, OHIO, ASSIGNOR OF ONE-HALF TO ROBERT E. MACKELLAR, OF ASHLAND, OHIO.

ADJUSTABLE DEFLECTOR FOR AUTOMOBILE-HEADLIGHTS.

1,369,227.

Specification of Letters Patent.

Patented Feb. 22, 1921.

Application filed February 19, 1920. Serial No. 359,774.

To all whom it may concern:

Be it known that I, WILLIAM ELLSWORTH, a citizen of the United States, residing at Ashland, in the county of Ashland and State 5 of Ohio, having invented a new and useful Adjustable Deflector for Automobile-Headlights, of which the following is a specification.

The object of my invention is to provide 10 an improved deflector, adjustably mounted within a headlight and adapted to prevent glare under all conditions and permitting of dimming the light when desired. It is a further object of my invention to provide a 15 means for adjusting the position of the deflector. These and other objects of my invention I attain by the mechanism shown in the accompanying drawings, in which:

Figure 1 is a side elevation of an automobile on which the device is mounted;

Fig. 2 is a front elevation of the invention with the deflector in lowered position;

Fig. 3 is a vertical section; and

Fig. 4 is a front elevation with a portion 25 of the lamp reflector broken away to show the means for operating the deflector.

Like numerals designate like parts in each of the views.

Referring to the accompanying drawings, 30 there is illustrated a conventional headlight casing 1, having a reflector 2 surrounding the lamp bulb 3. Directly above the lamp bulb 3 I provide an elliptical opening 7 in reflector 2, and a deflector 4 of the shape 35 illustrated in Fig. 3, mounted by hinges 6 to reflector 2 and having a rim 5 adapted to engage the reflector 2 about the opening 7, as shown in Fig. 3.

Attached to deflector 4, by a suitable pivot 40 9, is a link 8 which operatively connects it to bell-crank 11, which is pivoted to a suitable bracket 12, attached to the back of the lamp casing 1. A suitably curved link 14 is pivotally connected at 13 to bell-crank 11, 45 and at 15 to a second bell-crank 16. Bell-crank 16 is pivotally mounted on a suitable bracket 20 attached to the lamp casing 1, as shown in Fig. 3. A spring 17, attached 50 to any suitable portion of bell-crank 16, holds it normally in position, shown in full lines in Fig. 3, in which position the deflector 4 is held in its uppermost position. I provide a suitable operating wire or cable 19 suitably attached at 18 to bell-crank 16 55 and extending back over suitable guide pulleys 22 to a convenient portion of the ve-

hicle, where it is attached to a suitable operating lever 23, such as that as is illustrated in Fig. 1, which may be mounted on the steering-wheel of the vehicle, or under 60 the steering-wheel, or, in the case of a motorcycle, on one of the handle-bars. In operation, the deflector 4 is normally held in its uppermost position, as shown in full lines in Fig. 3, by reason of the tension of 65 the spring 17 on bell-crank 16, which is operatively connected to deflector 4 in the manner illustrated in Fig. 3. It is prevented from moving too far upward by the rim 5. In this position, the rays of light 70 that would normally strike on the reflector immediately above the light are deflected downward, by reason of the cupped shape of the deflector. When it is desired to further dim the lamp, by operating lever 23 the 75 deflector 4 is lowered so as to partially cover the lamp bulb 3, as shown in dotted lines in Fig. 3. The deflector 4 is prevented from striking bulb 3 by means of a suitable stop 80 24. It will be observed that in its dimming 80 position the deflector operates to prevent glare from the headlight; and in its non-dimming position rays of light are deflected to a substantial extent to partially dim the light.

What I claim is:

1. In an adjustable deflector for headlights, the combination of a headlight having a conventional reflector, said reflector having an elliptical opening positioned directly over the lamp bulb, a cupped deflector horizontally attached to the lower portion of the opening in the reflector and normally seated in said opening, said deflector having a flange on its free edge adapted to 90 engage the portion of the reflector adjacent the opening, spring controlled means mounted on the lamp casing operatively connected with the deflector normally holding same in elevated position, and means to swing the deflector to lowered position to partially cover the lamp bulb and dim the lamp to the extent desired.

2. In combination with the apparatus described in claim 1, flexible operating means 105 adapted to operate the deflector from a distant portion of the vehicle, said operating means being attached to the spring controlled means connected with the deflector above described.

WILLIAM ELLSWORTH.
